CLOTHES DRYING RACK

Arthur C. Shoener, Garrett, Ind.

Application March 24, 1950, Serial No. 151,597

2 Claims. (Cl. 211—119)

1

This invention relates to new and useful improvements and structural refinements in clothes drying racks, and the principal object of the invention is to provide a device of the character herein described which is particularly adapted for indoor use and which may be readily adjusted so as to vary the space between clothes hung thereon so as to assure proper drying.

Some of the advantages of the invention reside in its simplicity of construction, in its efficient operation, and in its adaptability to economical manufacture.

With the above more important objects and features in view and such other objects and features as may become apparent as this specification proceeds, the invention consists essentially in the construction and arrangement of parts as shown in the accompanying drawings, in which:

Figure 1 is a fragmentary under side perspective view of a roof or ceiling, showing the invention secured to the rafters or joists thereof;

Figure 2 is a perspective view of the invention in an inverted position and with the clothes supporting rods thereof removed; and

Figure 3 is an elevational view of one of the clothes supporting rods.

Like characters of reference are employed to designate like parts in the specification and throughout the several views.

Referring now to the accompanying drawings in detail, the invention consists of a clothes drying rack which is designated generally by the reference character 10 and embodies in its construction a substantially U-shaped frame 12 including a pair of spaced parallel side members 14 having upturned portions 16 at one end thereof connected together by a bight portion 18 substantially as shown.

The entire rack is formed from wire, and it is to be noted that the wire of the frame 12 is coiled so as to provide a pair of loops or eyes 20 at the junction of the bight portion 18 and the respective upturned portions 16. These eyes are intended to receive suitable fastening elements such as nails or screws 22 whereby the rack may be secured at one end thereof to one of the rafters or joists 24 of a flat roof or ceiling 26, while the remaining end portion of the rack is similarly mounted by means of an inverted U-shaped member 28 which includes a pair of downwardly projecting limbs 30, provided at their lower ends with a pair of eyes 32 which are slidable on the aforementioned side members 14, so that the distance of the member 28 from the bight portion 18 may be increased or

2

decreased so as to conform to the spacing of the rafters or joists 24.

The supporting member 28 is provided at the upper ends of the limbs 30 with additional eyes 34 to receive further fastening elements 36 for securing the supporting member to the joist or rafter, and it is to be noted that the free end portions of the side members 14 are upturned, as indicated at 38, the purpose of which will be hereinafter described.

A plurality of clothes supporting rods 40 are provided with upturned end portions 42 terminating in eyes 44 which are slidable on the side members 14 of the frame 12, by means of which arrangement the rods 40 may not only be adjusted as to their mutual spacing, but may also be completely removed from the side members when so desired. The latter may be achieved by simply removing the fastening elements 36 and 20 sliding the eyes 32 off the side members 14, whereupon one or more of the rods 40 may be slid off the side members over the upturned end portions 38. These upturned end portions will effectively prevent the rods 40 from sliding off the side members unintentionally after the removal of the supporting member 28, in the event that the frame 12 should become tilted downwardly from its normal, substantially horizontal position.

30 It is believed that the advantages and use of the invention will be clearly understood from the foregoing disclosure and accordingly further description thereof at this point is deemed unnecessary.

35 Having described the invention, what is claimed as new is:

1. In a clothes drying rack, the combination of a substantially U-shaped frame disposed in a horizontal plane and including a pair of spaced parallel side members having upturned portions at one end thereof provided at their upper ends with a pair of eyes, and a bight portion spaced upwardly from said side members and extending transversely between said eyes, fastening elements extending through said eyes for securing said frame to the under side of a supporting structure, an inverted U-shaped member adapted to be secured to the stated supporting structure and including a pair of downwardly extending limbs provided at their lower ends with eyes 45 slidable on the free end portions of the respective side members, and a plurality of rods extending transversely between said side members, said rods being provided at the opposite ends 50 thereof with eyes slidable on the respective side

3

members between said limbs and the upturned portions of the side members, whereby mutual spacing of the rods may be varied.

2. The device as defined in claim 1 wherein free end portions of said side members are upwardly arcuated.

ARTHUR C. SHOENER.
